UNITED STATES PATENT OFFICE.

HORACE M. SMITH, OF CHICAGO, ILLINOIS, ASSIGNOR TO LIQUID CARBONIC COMPANY, OF CHICAGO, ILLINOIS, A CORPORATION OF ILLINOIS.

BOTTLE-FILLING MACHINE.

Application filed July 19, 1918. Serial No. 245,605.

To all whom it may concern:

Be it known that I, HORACE M. SMITH, a citizen of the United States, residing at Chicago, in the county of Cook and State of Illinois, have invented certain new and useful Improvements in Bottle-Filling Machines, of which the following is a specification.

My invention relates more particularly to filling machines employed for filling charged liquids such as carbonated water and the like but in some of its features it is applicable to the filling of uncharged liquids. In filling charged liquids it is desirable to secure as high a content of gas as possible in the liquid as it is actually discharged into the bottles, and with this in view it has been the practice, before flowing the liquid into the bottle to be filled to fill the bottle with gas or air under a pressure almost equal to the sum of the gas or air pressure on the filling tank and the hydrostatic pressure of the column of liquid from the level of the bottle to the top of the liquid in the filling tank. When the liquid flows into the bottle against this counter-pressure the rate of flow is slow, the liquid is under continuous pressure and there is little release of the gas with which the liquid is charged in consequence. Ordinarily the liquid is charged into the bottles at the same pressure at which it is charged or impregnated with gas. The high pressure, however, is difficult to maintain and handle and results in frequent breakage of bottles and great loss of gas, particularly when the bottles have to be transferred from the filling machine to a topping or corking machine in the uncovered condition. I have found that by charging or impregnating the liquid to the saturation point, or substantially so, under a pressure considerably in excess of that ultimately desired and then reducing the pressure to that desired by passing it through a suitable pressure reducer, taking due precaution that the gas is not released during the reduction or during the flow to the filling tank and the bottles, I am able to secure and preserve a condition of supersaturation of the liquid and to fill it into the bottles at relatively low pressure without substantial loss. This method of operation forms the subject matter of a Patent No. 1,275,622 granted to me August 18, 1918. The present invention relates in part to the

apparatus which I have devised for practicing said process. It further relates to means for controlling the pressure reducer according to the counter-pressure against which the filling operation is effected.

Ordinarily in the filling of bottles a machine is employed in which an annular filling tank receives the liquid to be bottled and discharges it into the bottles to be filled through a number of filling heads connected to and communicating with the bottom of the tank, the filling being performed automatically by rotating the tank, feeding bottles to the successive filling heads as they are brought in turn to the feeding point, opening the valves controlling the supply of gas and liquid to the bottles by raising the bottles and filling heads as they travel around with the tank. A certain pressure, dependent on the pressure of the gas in the charged liquid, is supplied to the tank and a corresponding counter-pressure to the bottles. It sometimes happens in the operation of machines of this character, that breakage occurs or the bottles jam or become caught in the filling heads due to defects or irregularities in the bottles and it is desirable under these circumstances to immediately stop the machine until the broken or defective bottle is removed and at the same time to stop, during the stoppage of the machine, the flow of liquid to the tank. I have therefore interposed between the driving means and the rotary part of the machine a clutch operated by pneumatic pressure and provided with means whereby in the event of such breakage or jamming of the machine the clutch is immediately uncoupled and further damage is prevented. Other features of the invention will be apparent from a consideration of the following specification and claims and the accompanying drawings. It is to be understood, however, that the specific disclosure of the preferred form of my apparatus made herein is for the purpose of exemplification only and that the scope of the invention is defined in the following claims in which I have endeavored to distinguish it from the prior art so far as known to me without, however, relinquishing or abandoning any feature or portion thereof.

Referring to the drawings, Fig. 1 is a central vertical section through the upper part of a filling machine of the type to which my

invention is applied, parts being shown in elevation; Fig. 2 a side elevation of the entire machine and associated elements; Fig. 3 a central vertical section, of the preferred 5 form of pressure reducer on an enlarged scale, parts being shown in elevation; Fig. 4 a similar section of another detail; Fig. 5 is an axial section through a pneumatic clutch employed in connection with my invention; 10 Fig. 6 a plan of a detail on an enlarged scale; Fig. 7 a horizontal section on an enlarged scale of another detail; Fig. 8 another detail in elevation; and Fig. 9 yet another detail in plan.

15 The same reference character is applied to each part wherever it occurs in the several views.

Referring first to Figs. 1 and 2, the filling machine shown therein is in the main, and 20 except in the respects hereinafter pointed out, of a well-known construction. A substantial base 8 of cast metal or the like supports a column or standard upon which is journaled a rotating sleeve 9 carrying a 25 frame 10. Said frame supports an annular coaxially arranged filling tank 11 from the bottom of which project filling valves 12 slidingly mounted in and communicating with the interior of the tank and carrying 30 centering bells 13 at their respective ends. In the figures only a few of these filling valves are shown but it is to be understood that they are arranged at frequent intervals entirely around the tank. Beneath the tank 35 a spider 14 is carried by the rotary head or frame and a series of plungers or followers 15 corresponding in number and position to the filling valves are slidingly mounted in said spider. For the sake of clearness, in 40 Fig. 2, only a relatively small number of these plungers are shown. The plungers are operated by arms 16 pivoted on a flange 17 on the sleeve 9 of the rotating head or support, said arms being connected to their re- 45 spective plungers by pitmen 18 and also having rollers 19 which bear upon a flange 20 on the stationary base of such form that after the plungers receive the bottles at the entering position of the machine they are 50 raised successively by the cam operating on the rollers of the arms, thus forcing the mouths of the bottles into the respective filling valves, and raising the latter thus opening the valves and permitting the bottles to 55 be filled with liquid in a manner hereinafter described.

The filling tank is supplied with liquid 60 through a pipe 21 extending through the pedestal or standard on which rotates a union 22 carried by the head, the joint between the union and pipe being provided with a stuffing box at 23. From the union branch pipes 24 supply the liquid to the tank. The tank and the bottles are supplied 65 with gas or air under pressure from a com-

mon source through the pipe 25 which is connected to the high pressure air chamber axially as at 26. The details of this construction are well known and in common use and therefore need not be described. The 70 high pressure air chamber 27 is connected to the filling valves by pipes 28 so that the bottles receive the air from chamber 27 at full pressure. Chamber 27 is surrounded by a second chamber 29 which receives air from 75 the chamber 27 but at a somewhat reduced pressure, this pressure reduction being due to the hydrostatic pressure of the water 30 contained in chamber 29, the air escaping into chamber 29 only after it has displaced 80 the water from high pressure chamber 27 sufficiently to permit the air to escape through the perforations at the bottom of the wall of the latter. The low pressure air chamber 29 is connected by pipes 31 to the 85 space above the liquid in the filling tank. Water to a proper amount may be charged into the chamber 29 through the cock 32, it being necessary for the most efficient operation of the machine that the hydrostatic 90 pressure of the water 30 opposing the air pressure in the chamber 27 be equal to the hydrostatic pressure of the liquid in the tank on the bottles when the latter are filled to the required height. 95

As each bottle is raised by the mechanism heretofore described the bell top first opens the connection to the high pressure air chamber, thus giving the bottle the required counter-pressure and then opens the liquid 100 valve by which the liquid is permitted to flow into the bottle under its hydrostatic pressure plus the gas or air pressure of the tank and against the counter-pressure in the bottle. As the bottle fills with liquid, the counter-pressure gas contained therein is driven back into the tank 29 until the level of the liquid in the bottle is such that equilibrium is reached when the further flow of liquid to the bottle ceases. After the filling 105 operation is completed the further rotation of the bottle and its support brings it to the point on the stationary cam where the bottle is again lowered and in position to be fed out from the machine with its contained 110 liquid. 115

The rotation of the machine is effected by means of an electric or other motor 33, a pinion 34 on the shaft whereof drives a gear 35 fast to one member of a clutch to be presently described, the other member of which is fast to a gear 36 meshing with an idler gear 37 which in turn engages a gear 38 formed integrally with a bevel pinion 39, (see dotted lines in Fig. 2). The latter 125 drives an upright shaft 40 by engaging a bevel pinion 41 thereon and shaft 40 carries at its lower end a pinion 42 and the latter drives a pinion 43 which meshes with and drives a circular rack 44 upon the tank 130

spider. While the above is a satisfactory arrangement of gearing, obviously it is only one of many that might be employed for the purpose.

5 Returning to the clutch it will be seen that the gear 35 is cast with a concentric chamber section 45 and the latter is formed with a hub 46 projecting thereinto for a purpose which will presently appear. The driving member 47 of the clutch is within the chamber casting 45 and mounted for axial movement relative thereto and provided with perforated bifurcated lugs 48 which embrace studs or pins 49 projecting inward 10 from the wall 50 of said chamber casting. Between said wall and lugs and surrounding the respective pins 49 are springs 51 which tend by their expansion to force clutch member 47 axially away from the driven 15 clutch member 52. The latter is rotatively journaled in the hub or hollow boss 46 of the chamber casting 45, being formed for this purpose with a hollow hub 53 which receives the reduced end 54 of the shaft 55 on 20 which gear 36 heretofore mentioned is mounted. The hub 53 is clamped between an outside washer 56 upon said shaft and a smaller washer 57 secured to the end 54 of the shaft by a screw 58. The hub 46 is 25 loosely embraced between the disc portion 59 of the clutch member and the washer 56 so that relative rotary movement but no axial movement between the casting 45 and the inner clutch member is possible. A dia- 30 phragm 60 is secured over the open side of the chamber 45 by means of a cap plate 61 which is bolted to the casting 45 by bolts 62, (see Fig. 5). The cap plate 61 is slightly concave as shown forming an air chamber 35 63 which is supplied with air through a pipe 64 which is suitably packed by gland 65. From the above description of the construction it will be understood that when there 40 is no air pressure in the chamber 63 or insufficient pressure to overcome the spring 51 the clutch members are separated at their conical surfaces so that the driving member is free to rotate without rotating the inner driven member. When, however, sufficient 45 pressure is applied to the chamber 63 the clutch members are engaged and rotated in unison by the motor and so drive the spider. 50

In the construction shown the pipe 64 is connected through a pressure reducer 66 and 55 pipe 67 to a suitable source of air pressure, the regulator or reducing valve 66 reducing the pressure to just what is necessary to maintain the clutch members in engagement during the normal operation of the machine. 60 As seen in Figs. 2 and 8 there is a by-pass 68 about said reducing valve which is controlled by a starting valve 69 (see Fig. 7). Obviously a much looser engagement between the clutch members is necessary after 65 the inertia of the parts is overcome and they

are set in rotation than is required to start the machine, and as it is desirable for reasons which will presently appear that the pressure in the clutch chamber be no greater at any time than is essential, I have provided this by-pass so that the full pressure of the source may be employed to start the machine and then any further access of air be regulated by the reducing valve so as to reduce the pressure to the minimum required. I have shown the valve 69 as comprising a casting 70 having a valve chamber 71 closed by a cap 72 and a valve 73 seating therein with the pressure. 74 indicates the inlet to the valve casing and 75 the 70 outlet. The valve member 73 is provided with a stem piece 76. When the machine is to be started the stem piece is depressed with the thumb by the operator who is obliged, however, to release it before he is 75 free to arrange the bottles in the bottle-feed so that there is no possibility of maintaining the valve 73 open longer than is required to start the machine. At some suitable point as at 77, see Fig. 8, I have arranged a leak 80 opening whereby the pressure in excess of that supplied through the pressure-reducing valve is permitted to exhaust during the normal operation of the machine. It will thus be seen that in starting the machine after a 85 stoppage the operator opens the valve 69 which permits the full pressure to enter the diaphragm chamber of the clutch and to cause the clutch members to firmly engage each other. By this means the machine is 90 started in rotation through the mechanism heretofore described. After the machine has started the operator necessarily releases the valve 69 to handle the bottle which valve 95 thereupon returns to its seat thus cutting off the direct supply of full air pressure. The pressure is then supplied through the pressure reducer 66 which reduces it to the degree necessary to maintain the engagement of the clutch during normal operation. 100 The pressure in the system beyond the pressure reducer quickly drops to that for which the latter device is set by reason of the leakage through a hole 77. A pressure gauge is 105 shown at 78, a check valve for preventing back-pressure through the pressure gauge at 79 and an ordinary turning plug at 80 for cutting off the supply when desired. 110

In machines of this character the filling valves occasionally stick in a raised position with the bottles attached thereto, because of the jamming of the filling tube in the neck of the bottle due to irregularities in the latter. When this occurs, for obvious reasons, it is desirable to stop the machine before the nozzle affected, with its bottle, reaches the position for the discharge of the bottle from the machine. In order to effect this stoppage automatically I provide at 81, see Fig. 2, an exhaust valve 115 120 125 130

which is operated by any belltop which has stuck in the raised position and which is connected by pipe 82 with the air supply pipe 64 for the clutch so as to immediately 5 reduce the pressure in the pneumatic chamber of the clutch when the valve is open. The valve may be of any desired character but I have shown it as an ordinary reciprocating valve 83, the stem 84 of which projects 10 outside the valve casing in position to be operated by an arm 85 pivoted at 86 to a bracket, see Fig. 6. The bracket is connected to the stationary part of the machine in such a location and is so arranged that the 15 arm 85 will clear the filling tubes 12 as the filling tank revolves so long as said tubes are in the normal lowered position. When, however, a belltop fails to return to its lowermost position, as for example, by the sticking 20 of a bottle on the filling tube, it engages the arm 85 which, as the belltop wipes past it, is repressed against the stem 84 of the valve and opens the latter releasing the pressure in the pneumatic chamber in the 25 clutch and permitting the clutch to open and stop the machine.

It is also desirable to stop the machine when for any reason the bottles become jammed in feeding them to the several supports by which they are raised into the filling 30 position as before described. Commonly in machines of this character the bottles are fed along the guideway in a constant stream or procession, single file, at a speed and under 35 sufficient pressure from behind to drive them into the successive bottle supports as the latter are presented to the feeding mechanism. The end section 88 of the wall 89 of the bottle guide or channel is pivoted as at 40 90 and yieldingly maintained in position by a spring 91. If, for any reason the bottles jam in the channel they force the pivoted wall backward to enlarge the space at the end of the channel (see Fig. 9). The 45 pivoted section 88 has a depending portion 92 and an exhaust valve 93 is connected to the by-pass 68 and so located with reference to said depending portion 92 of the pivoted wall section that its stem 94 is adapted to be 50 struck by the latter when said pivoted section is pressed back by the jamming of the bottles, as heretofore described. The operation of the valve 93 permits the flow of air from the tube 64 to the atmosphere thus 55 reducing the pressure in the pneumatic clutch and stopping the machine. The purpose of normally maintaining only such a pressure in the pipe 64 and pneumatic chamber of the clutch, as will suffice to hold the clutch 60 in engagement will now be obvious as it is essential to the most effective operation of the machine that it be stopped immediately when irregularities of the kind above described occur in the operation of the machine, and this can only be accomplished by 65

keeping the pressure just above that essential to maintain the clutch members in operative engagement.

In an earlier portion of the specification I have described the chambers 27, 29 for 70 maintaining the required difference in pressure between the tank above the liquid and the bottles being filled. I further refer to the pipe 25 for supplying the air under the requisite pressure to the chamber 27. Obviously the air for supplying the pressure to the tank and bottles might and ordinarily would be taken from the same source of supply as that which controls the pneumatic clutch. In the particular embodiment of the invention chosen for illustration I have shown the air for the tank as supplied from a separate source by means of a pipe 95 leading to chamber 96 from which air is conducted by pipe 97 to pipe 25 and thence 80 to the tank. The pressure in the chamber 96 is shown by gauge 99.

The liquid to be filled is fed from the carbonator represented diagrammatically at 100 to a pressure reducer 101 and thence by pipe 102 to the axial pipe 21 heretofore described by which it is conducted to the revolving union 22 and thence by pipes 24 to the tank. In the pressure reducer the liquid which has been charged at a much higher pressure than 95 that under which it is to be filled, say fifty pounds, is reduced in pressure to the condition in which it is to be filled, say twenty-five pounds. This pressure reduction is effected by a valve under certain counter-weight and controlled from the gas or air pressure supplied to the tank and bottles as heretofore described. It will be apparent from what has gone before that in order to 100 secure quiet filling of the liquid the difference in pressure between the counterpressure gas or air and the liquid be maintained constant as a change in the relative pressure must result either in a stoppage of the flow of the liquid or objectionable foaming. By my improved arrangement I combine the regulation of this difference in pressure with the hereinbefore described reduction in pressure of the liquid to be filled. By 105 properly conducting the pressure reduction 110 and the transfer of the liquid from the pressure reducer to the tank and bottles, the release of gas with which the liquid has been charged is almost entirely prevented notwithstanding the reduction in pressure resulting in a condition of supersaturation during which the liquid is charged into the bottles. The method of supersaturation and charging the supersaturated liquid into the 115 bottles forms the subject-matter of the patent referred to above.

Referring now more particularly to Fig. 3, the pressure-reducer 101 referred to above comprises a main casting or shell 103 having the opposite sockets 104, 105 for the 120 125

inlet and exhaust pipes 106, 107, leading respectively from the carbonator and to the pipe 101 by which the liquid is conveyed to the filling machine. A neck 108 cast with 5 the housing or shell 103 leads to an interior valve chamber 109 open at its upper and lower ends, the upper end being provided with a cover plate 110 upon which the valve seat 111 is formed and the lower open end 10 of the valve chamber being screw-threaded at 112 to receive an annulus 113 on which the lower valve seat is formed. Upon a stem 114 is mounted a sleeve 115 the upper end of which is flanged as at 116 to form 15 a support for the upper valve washer 117. Said washer is maintained in place by an annulus 118 having a projecting lip 119 bearing on the outer edge of said washer, said annulus being in turn held in position 20 by an internally threaded ring 120 engaging a thread on the periphery of the flange 116 and having an inwardly directed flange 121 extending over and engaging said annulus. The lower valve comprises an annulus 25 122 which is secured upon the valve stem and supports the washer 123. Said washer is secured at its edges by an annulus 124 which in turn is held by an internally threaded ring 125 screwed upon the 30 annulus 122. The latter is formed with an upwardly extending sleeve or hub 126 threaded exteriorly and receiving lock nuts 127, 128 by which the inner edge of the washer is held in place on the annulus 122. 35 The latter is clamped by a nut 129 screwed upon a reduced portion of the valve stem 114. The sleeve 115 is maintained against upward movement relative to the stem 114 by a casting 130 to be later described. 40 The shell or casing 103 is closed at the lower opening 131 by a cap plate 132, the before-mentioned stem being reduced at 133 and projecting axially through said cap plate and packed with reference thereto at 134. 45 The opening of the balanced valve is opposed by a counterweighted lever 135 which is fulcrumed by means of a ball-bearing at 136 to a stationary bearing bracket 137 on the stand, the short end 138 of said lever being recessed or hollowed to receive the lower 50 end of a thrust rod or link 140 the upper end of which is headed or rounded as at 141 to bear in a cavity 142 in the lower end of the valve stem. The latter is threaded to receive a cap 143 by which the headed link 55 or thrust rod is secured to the valve stem, without, however, preventing free angular movement relative thereto. The weight on the lever is shown at 144. In the construction shown the reducing chamber is supported by a hollow standard 145. The upper opening 146 of the casing or shell is closed by a domed cover 147 which is formed at 148 with a guide for the upper 60 end of the valve rod. Between the flanges 149, 150 on the dome and shell respectively is clamped a diaphragm 151 of rubber or other suitable flexible material which not only packs the joint but, in conjunction with the casting 130, referred to above, serves to 70 separate the liquid chamber of the shell from the air chamber of the dome. The casting 130 is formed with a downwardly projecting sleeve 152 which bears against sleeve 115 above described and maintains the latter in 75 position, the casting itself being prevented from upward movement on the valve stem which it surrounds, by nuts 153 screwed upon said stem. The diaphragm 151 is annular, the central opening receiving the circular shouldered projection 154 on the casting and the inner edge of said diaphragm being secured to casting 130 by an annulus 155 bolted to the latter. The air or gas space within the dome 147 is connected by a pipe 80 156 to the chamber 96 whereby the pressure within the dome is normally that of the gas or air supplied to the tank and bottles. For obvious reasons it is desirable that 85 the flow of liquid to the tank be cut off whenever the machine is stopped. This is accomplished in my apparatus by relieving the pressure in the dome 147 at the same time that it is relieved in the clutch. For this purpose I provide an air relief valve 90 mechanism 157, see Figs. 2 and 4, which is controlled by the pressure in the piping leading to the pneumatic clutch and which controls an escape from the dome 147. Valve mechanism 157 comprises a casing 100 158 divided by diaphragm 159 clamped between the sections of said casing, as shown in Fig. 4. The upper half of the casing communicates through an opening 160 with pipe 161 leading to the pipe 64 by which 105 the pneumatic clutch is controlled. The lower section of the casing beneath the diaphragm is connected by a pipe 162 to said dome 147. A valve seat 163 is formed on an inwardly projecting perforated boss 164 110 and is controlled by a valve connected to the diaphragm 159. This valve comprises an exteriorly threaded thimble 165 which is secured to the diaphragm by means of a threaded plug or extension 166 formed on 115 the guide member 167 below the flange 168 thereof. The screw plug 166 extends through the diaphragm, the adjacent edge of which is clamped between flange 168 and flange 169 on the thimble 165. A stem 170 120 on the guide member extends into a bearing boss 171 on the upper half of the casing to guide said stem and the valve attached thereto. The valve washer 172 is secured to the thimble 165 by means of the interiorly 125 threaded and flanged annulus 173 which screws upon said thimble. Between the flange 169 on the thimble and the bottom 174 of the casing is a spring 175, the resistance to compression of which is determined 130

6

by the pressure to be maintained in the dome 147. A small outlet passage 176 maintains the interior of the lower half of the casing at atmospheric pressure. The 5 pressure of the counterpressure air or gas in the upper half of the casing is sufficient under normal conditions to maintain the valve firmly on its seat against the pressure of the spring 175. Thus the pressure 10 in the dome is normally maintained at that required to sufficiently overbalance the weighted lever 135 to secure the desired reduction in pressure of the liquid. When, however, the pressure in the system controlling 15 the pneumatic clutch falls, for any reason, thereby opening the clutch, the pressure on the diaphragm 159 correspondingly falls and the valve in the casing 158 rises putting the interior of the dome 147 into 20 communication with the atmosphere a sufficient length of time to reduce the pressure in said chamber to that desired, preferably to four pounds. In order that this may be accomplished notwithstanding the connection 25 of the dome space to the counterpressure gas supply, the communication between the dome and the pipe 156 must be made very minute and for this purpose the opening 177 through the base of the socket 178 30 which receives the pipe 176 is made very fine. The exhaust valve when open readily takes care of the gas supplied through the aperture 177 but when closed such aperture is sufficient to quickly restore the counterpressure in the dome. When the operating 35 pressure in the piping 64 and in the upper half of the casing 158 is restored it again closes the valve. In the meantime, however, the balanced valve in the pressure 40 reducer is closed shutting off the supply of liquid which remains cut off until operating pressure is restored in the piping 64.

The pressure reducer constructed as shown and described above is exceedingly delicate in its operation and responds to the slightest variations in pressure. The position of the valve with reference to its seat is controlled by three forces, to wit, the liquid pressure on the diaphragm, the gas 45 pressure on the opposite side of the diaphragm, and the force exerted by the mechanical system comprising the lever 135, the weight of the valve and connected parts, and the counterweight 144, the valve 50 itself being substantially balanced. It follows that within limits the weight 144 can be so adjusted that the valve will be in equilibrium when off its seat with any desired difference in pressure between the gas and 55 the liquid. On any slight increase in the pressure of the liquid beyond the valve the latter moves towards its seat and conversely on any slight decrease in the pressure beyond the valve the latter moves from 60 its seat, but by reason of the delicacy of the 65

mechanism these movements are almost infinitesimal in extent. They are sufficient, however, to maintain the speed of flow of the carbonated liquid constant and thereby avoid the release of gas due to variations 70 in the speed of movement of the liquid being filled.

I claim:

1. In a machine for filling charged liquids into bottles, a filling tank, a carbonator, a 75 connection between the carbonator and tank for supplying the latter with charged liquid, a pressure reducer in said connection, means for continuously supplying the tank with counterpressure gas, and means 80 controlling the pressure reducer from the pressure of said gas.

2. In a machine for filling charged liquids into bottles, a filling tank, a carbonator, a 85 connection between the carbonator and tank for supplying the latter with charged liquid, a pressure reducer in said connection, means for continuously supplying the tank with counterpressure gas, a counterweighted valve in said pressure-reducer, a diaphragm 90 connected to said valve, a pneumatic chamber to which said diaphragm is exposed and a connection from the source of counterpressure gas to said chamber.

3. In a machine for filling charged liquids 95 into bottles, a filling tank, a carbonator, a connection between the carbonator and tank for supplying the latter with charged liquid, a pressure reducer in said connection, means for continuously supplying the tank with 100 counterpressure gas, a pneumatic chamber, a diaphragm exposed to the pneumatic chamber and controlling the valve of the pressure-reducer and a normally closed valve opened when the machine stops for 105 reducing the pressure in said chamber.

4. In a machine for filling charged liquids into bottles, a filling tank, a carbonator, a connection between the carbonator and tank for supplying the latter with charged 110 liquid, a pressure reducer in said connection, means for continuously supplying the tank with counterpressure gas, a rotary support for the filling tank, means for rotating said support including a motor, a 115 clutch intermediate said motor and the rotating support, a pneumatic chamber, the pressure wherein controls the clutch, a second pneumatic chamber connected with the means for supplying counterpressure gas 120 and the pressure wherein controls the pressure-reducer, a connection between the pneumatic chamber of the clutch and the pneumatic chamber controlling the pressure-reducer, and means common to said 125 chambers for reducing the pressure therein to stop the machine and close the valve of the pressure-reducer.

5. In a machine for filling charged liquids into bottles, a filling tank, a carbonator, a 130

- connection between the carbonator and tank for supplying the latter with charged liquid, a pressure-reducer in said connection, means for continuously supplying the 5 tank with counterpressure gas, a rotary support on which the tank is mounted, a motor and intermediate mechanism for rotating the support, a clutch in said mechanism, a pneumatic chamber controlling the clutch, 10 a pneumatic chamber controlling the pressure-reducing valve, a connection from the last said chamber to the means for supplying counterpressure gas, a valve for exhausting the last-mentioned pneumatic 15 chamber, a diaphragm controlling said exhaust valve, a pneumatic chamber to which said diaphragm is exposed, a connection from the last said pneumatic chamber to the chamber controlling the clutch, and a 20 valve for reducing the pressure in the last said pneumatic chamber and in the pneumatic chamber controlling the clutch.
6. In a machine for filling charged liquids into bottles, a filling tank, a carbonator, a 25 connection between the carbonator and tank for supplying the latter with charged liquid, a pressure-reducer in said connection, means for continuously supplying the tank with counterpressure gas, a rotating 30 support for the tank, a motor and intermediate mechanism including a clutch for rotating the support, a pneumatic chamber 63 and diaphragm 60 controlling the clutch, piping for supplying said pneumatic 35 chamber with gas pressure, a valve adapted to exhaust the pressure in said piping to stop the machine, the said pressure-reducer including a valve, a pneumatic chamber 147 and diaphragm 151 controlling the 40 valve of the pressure-reducer, a connection 156 from said chamber to the means for supplying counterpressure, a valve mechanism 157 for exhausting chamber 147, a pneumatic chamber and dia- 45 phragm 159 for controlling said valve, and a connection 161 from the last said chamber to the piping 64 whereby a reduction of pressure in said piping system for stopping the machine also permits the exhaust 50 valve to open and relieve the pressure in chamber 147.
7. In a machine for filling charged liquids into bottles, a filling tank, a carbonator, a connection between the carbonator and tank 55 for supplying the latter with charged liquid, a pressure reducer in said connection, means for continuously supplying the tank with counterpressure gas, a rotating support for the tank, a motor and intermediate 60 mechanism including a clutch for rotating the support, a pneumatic chamber 63 and diaphragm 60 controlling the clutch, piping for supplying said pneumatic chamber with gas pressure, a valve adapted to ex- 65 haust the pressure in said piping to stop the machine, the pressure reducer including a valve, a pneumatic chamber 147 and dia- 70 phragm 151 controlling the valve of the pressure-reducer, a connection 156 from said chamber to the means for supplying counterpressure, said connection including a minute opening therefrom into chamber 147, a valve mechanism 157 for exhausting chamber 147, a pneumatic chamber and diaphragm 159 for controlling said valve and a connection 161 75 from the last said chamber to the piping 64 whereby a reduction of pressure in said piping system for stopping the machine also permits the exhaust valve to open and relieve the pressure in chamber 147. 80
8. In a machine of the class described, a filling tank, a series of reciprocating filling nozzles connected to said tank, a rotary support on which the filling tank is mounted, means for rotating said support 85 comprising a motor and intermediate mechanism, the latter including a clutch, a pneumatic chamber controlling the clutch, means for continuously supply gas to the pneumatic chamber, a valve and connections to 90 the pneumatic chamber for exhausting the latter, an arm controlling said valve, said arm being so located and arranged with reference to said tank and filling nozzles as to be struck by a nozzle out of normal 95 position to open the valve and release the air pressure in the chamber as the tank revolves.
9. In an apparatus of the class described, a filling tank for filling nozzles thereon, a 100 rotary support on which the tank is mounted, means for rotating the support comprising a motor, intermediate mechanism and a clutch in said mechanism, a pneumatic chamber controlling the clutch, 105 means for continuously supplying said chamber with pressure gas, a valve connected to said means for exhausting the pressure therein to open the clutch, a bottle feed comprising a channel, a wall section in said channel pivotally mounted and yieldingly held in position so as to yield when the bottles become jammed in said feed, said valve being provided with a stem and so located that when the pivoted wall section is forced 110 outward it engages said valve to open the same by reducing the pressure in the means supplying the pneumatic chamber of the clutch to stop the machine. 115
10. In a device of the class described, a 120 filling tank, a rotary support on which the tank is mounted, means for rotating the tank comprising a motor and intermediate mechanism, the latter including a clutch, pneumatic means for normally maintaining 125 the clutch members in engagement, a conduit for supplying said pneumatic means with gas under pressure, a pressure-reducer in said conduit, a by-pass around the pressure-reducer for supplying said conduit 130

with gas under full pressure and a hand-controlled valve controlling said by-pass.

11. In a device of the class described, a filling tank, a source of carbonated liquid, means for supplying the filling tank with counter-pressure gas, a conduit connecting the supply and the filling tank, a pressure reducer in said connection comprising a

diaphragm, a connection for exposing one side of the diaphragm to the counter-pressure, the other side of the diaphragm being exposed to the liquid, said pressure reducer adapted and arranged to maintain a constant amount of flow of the liquid. 10
